WASHING MACHINE

Simon Henri Stoffel, Delft, Netherlands, assignor
to N. V. Machinefabriek Reineveld, Haagweg,
Delft, Netherlands, a company of the Netherlands

Application July 16, 1931, Serial No. 551,216, and
in the Netherlands August 30, 1930

2 Claims. (Cl. 68—18)

This invention relates to a washing machine of the type known per se, in which a horizontally journalled perforated drum for the reception of the articles to be washed is capable of being turned to and fro within a closed shell which contains the soapy water or the other washing liquid. The perforated drum is usually subdivided by approximately radial partitions into two or three compartments, each of which compartments serves the purpose of receiving one set of washing, that is to say, a number of articles belonging together. To enable it to be filled and emptied each compartment is provided with one or more closable openings which lie next to one another in the axial direction and in each compartment directly adjoin one of the partitions, the arrangement being such that the angular distances between the openings correspond to the angle over which each compartment extends. In view of this arrangement it is necessary after the completion of a washing operation to bring the compartments successively with their openings opposite the filling and emptying openings provided at one side only of the shell for discharging them.

A washing drum having four compartments has also already been described. In this drum as well the charging and discharging openings of the compartments are arranged in the manner described above and the perforated drum must therefore be partly turned four times in order that all the compartments may be discharged and charged.

The present invention has for its object to improve such a washing machine having four compartments, in such a manner that two compartments can each time be simultaneously discharged and charged through oppositely positioned openings in the shell.

The single figure shown in the drawing represents a vertical cross sectional view of a compartmental washing machine.

The invention consists more particularly in this, that the openings of each two pairs of adjacent compartments are close to the partition and that the shell has two horizontally opposed charging and discharging openings, the angular distance of which corresponds approximately to that between two drum openings which follow one another in the peripheral direction but are not directly adjacent to one another.

A washing machine according to the invention shall now be more particularly described with reference to the accompanying drawing which illustrates it in vertical cross-section.

The horizontal perforated drum 1 is rotatably journalled within the stationary shell 2 and is subdivided by approximately radial partitions 3 into four compartments of equal size *a*, *b*, *c*, *d*. Each compartment has a charging and discharging opening *4a*, *4b*, *4c*, *4d* (or an axially extending row of such openings) which is capable of being closed by means of a cylindrically curved sliding door *5a*, *5b*, *5c*, *5d*. The openings *4a*, *4b*, *4c* and *4d* do not lie, in accordance with the usual principle, at angular distances of 90° each, but are so positioned that the openings *4a* and *4d* and the openings *4b* and *4c* are directly next to one another or approximately so.

The shell 2 has two openings (or axially arranged rows of such openings) 6, 7, the horizontal lower edges of which lie in the horizontal central plane of the shell. These openings can be closed by means of cylindrically curved sliding doors 8, 9.

When a washing operation is finished and the perforated drum 1 occupies the position shown in the drawing, the partitions 3 between the compartments *a*, *b*, on the one hand and the compartments *c*, *d* on the other hand being approximately horizontal (in which position they may be set by means of a pointer provided outside the shell), while the doors *5a*, *5b*, *8* and *9* are open, the compartments *a* and *b* can be simultaneously discharged and thereupon simultaneously charged.

With machines of this kind with the usual dimensions the openings 6 and 7 (and consequently the openings *4a*, *4b* lying temporarily opposite them) are situated at such a height above the floor that this operation can be carried out without the aid of raised platforms or the like. The washing can be removed without any difficulty from the compartments, as the lower edges of the discharge openings 6, 7 are approximately at the same height as the partitions which for the time being form the bottoms of the compartments *a* and *b*. Were the charging and discharging openings of the perforated drum at angular distances of 90° from one another, the opening *4b* would, when the opening *4a* is in the position shown, be approximately at the top and the compartment *b* would thus be very difficult to discharge, if in these circumstances it would be at all possible to work from both sides at the same time.

When the compartments *a*, *b* have been discharged and then recharged the drum need only be turned once through 180° in order that the compartments *c* and *d* can be attended to in

the manner described. The machine can then be immediately started. The advantage of the new construction resides in the fact that the charging and discharging operations require considerably less time and that the machine can therefore be longer in operation during one working hour, which is a matter of considerable importance in such relatively costly machines.

The idea underlying the invention can be similarly applied to washing machines having for instance six or eight compartments, although this would entail some difficulties.

What I claim is:—

1. A washing machine having a horizontal, perforated drum which is divided into four compartments by approximately radial partitions and is rotatable about a horizontal axis within a closed shell, each compartment being provided with only one opening adjacent a partition and

20

adjacent the opening in the adjoining compartment, said shell being provided with two horizontally opposed charging and discharging openings adapted to simultaneously register with a pair of compartment openings, and each opening being provided with a door.

2. A washing machine having a shell casing, a horizontal, perforated drum therein which is divided into four compartments by approximately radial partitions and is rotatable about a horizontal axis within the casing, each compartment being provided with an opening adjacent a partition and adjacent the opening in the adjoining compartment, said shell casing being provided with two horizontally opposed charging and discharging openings adapted to simultaneously register with a pair of compartment openings and each opening being provided with a door.
